UNITED STATES PATENT OFFICE

123,663

DESIGN FOR A LABEL BLANK

George W. Bristol, New York, N. Y.

Application June 15, 1940, Serial No. 93,029

Term of patent 14 years

To all whom it may concern:

Be it known that I, George W. Bristol, a citizen of the United States, residing at New York, in the county of New York, and State of New York, have invented a new, original, and ornamental Design for a Label Blank, of which the following is a specification, reference being made to the accompanying drawing, forming part thereof.

The figure is a plan view of a label blank showing my new design.

I claim:

The ornamental design for a label blank, as shown.

GEORGE W. BRISTOL.
